DESIGN FOR A LAMP HOUSING

John A. McKay, Coshocton, Ohio

Application June 8, 1939, Serial No. 85,405

Term of patent 14 years

To all whom it may concern:

Be it known that I, John A. McKay, a citizen of Canada, residing at Coshocton, county of Coshocton and State of Ohio, United States of America, have invented a new, original, and ornamental Design for a Lamp Housing, of which the following is a specification, reference being had to the accompanying drawing, forming a part thereof.

The figure is a perspective view of the lamp housing showing my new design. The appearance on the opposite side of the design is the same.

I claim:

The ornamental design for a lamp housing, substantially as shown and described.

JOHN A. MCKAY.
